(57) **CLAIM**

The ornamental design for a plug-in data storage cartridge, as shown and described.

DESCRIPTION

FIG. 1 is a right side elevational view of a plug-in data storage cartridge which forms my new design;

FIG. 2 is a left side elevational view thereof;

FIG. 3 is a bottom plan view thereof;

FIG. 4 is a top plan view thereof;

FIG. 5 is a front elevational view thereof; and,

FIG. 6 is a perspective view showing the front, top and right side thereof.

The broken line showing in FIG. 3 is included for the purpose of illustrating unclaimed portions of the plug-in data storage cartridge and form no part of the claimed design.
